UNITED STATES PATENT OFFICE

BENJAMIN B. EPSTEIN, OF BROOKLYN, NEW YORK, ASSIGNOR TO THE LEES MANUFACTURING COMPANY, OF NEW YORK, N. Y., A CORPORATION OF CONNECTICUT

TIE CORD

Application filed March 2, 1931. Serial No. 519,549.

This invention relates generally to cordage, and has particular reference to an improved construction of a decorative tie cord and method of producing the same, by virtue of which tie cords having various decorative effects may be obtained by combining the several elements in different ways.

10 Tie cords of this general nature which are used for various purposes, such as the tying of holiday gift packages, in the packaging of candies and other confections and the like, must possess sufficient tensile strength to accomplish their initial purpose of tying the package, as well as serving as a decoration.

15 It is, therefore, the principal object of the present invention to produce an improved tie cord of this nature, in which certain elements thereof combine to offer a uniform resistance to the pulling strains or stresses exerted 20 thereon.

More particularly, the invention resides in an improved tie cord of the indicated character which possesses the requisite tensile strength due to the fact that certain elements 25 of the cord, although of different characters or materials, have approximately the same degree of elasticity, thereby combining to simultaneously offer their united strength when placed under tension.

30 Other objects of the invention reside in the comparative simplicity of construction of the cord, the economy with which it may be produced and the general efficiency derived therefrom.

35 With the above recited and other objects in view, reference is had to the following description and accompanying drawings, in which there are illustrated several embodiments of the invention, while the claims define the actual scope thereof.

In the drawings:

Figure 1 is a side view of a length of tie cord constructed in accordance with the invention.

45 Figure 2 is an enlarged transverse sectional view therethrough taken approximately on the line indicated at 2-2 in Figure 1.

Figure 3 is a view similar to Figure 1, illustrating in modified form the invention.

Figure 4 is an enlarged transverse sectional view therethrough taken approximately on the line 4-4 of Figure 3.

Referring to the drawings by characters of reference, A designates generally what will be termed the core of the tie cord, which is made up of a number of strands 5 of a suitable inexpensive material, such as cotton yarn. The core A has a covering designated generally by the reference character B, which consists of a number of strands 6 of a more expensive material, such as rayon. The tie cord further includes a binding designated generally by the reference character C, which in the form of the invention illustrated in Figures 1 and 2 is made up of a number of strands 7 of a suitable material, such as rayon.

In the form of the invention illustrated in Figures 3 and 4, the binding, which is designated generally by the reference character D, is disclosed as a flat ribbon of tinsel or any equivalent material, which may be embossed or otherwise treated to provide a surface decoration or ornamentation designated by the reference character 8.

In either form, the core and its covering are of different materials and are twisted in the same direction, while the binding is spirally twisted about the said core and its covering in an opposite direction so that the covering strands are puffed up and away from the core strands and maintained in this condition by the binding, to give a peculiar bulky appearance to the portions of the core covering which lie between the convolutions of the binding without the necessity of employing a great amount of material. This produces an attractive decorative or ornamental tie cord, in which the core covering and the binding may be of contrasting colors or shades.

Due to the fact that the rayon binding C or ribbon tinsel binding D ordinarily possesses an inherently different degree of elasticity with respect to the core A, it follows that unless the elasticity of these elements is rendered approximately equal, strains or stresses exerted thereon will tend to cause the binding, which is usually the weaker of

the two, to break ahead of the cord. It is, therefore, important to overcome this condition in order that the binding and the core may offer their uniform strength when placed under tension and, hence, the elasticity of one or the other is increased or decreased or both are treated so as to render them of approximately the same degree of elasticity during their incorporation in the tie cord structure.

The method of producing the tie cord includes the steps of twisting together, in the same direction, the strands of the core and simultaneously applying at an angle the covering during the twisting of the core strands together, the core strands being fed under a tension to reduce their elasticity to the desired degree. The binding is then applied by helically winding the same in an opposite direction to the direction of the twist of the core and binding strands. During the application of the binding, the covered core is subjected to an additional tension while the binding is placed under a sufficient tension to equalize the elasticity of the core and binding in the finished product. While the binding is being applied and twisted in an opposite direction to that of the twist of the core and its covering, the covering and core are caused to slightly untwist and thus cause the covering strands which are more resilient than the core strands to puff up about the core between the convolutions of the binding whereby the puffed up portion is bulkier than the periphery of the core and the outer periphery of the helix forming the binding, while said puffed up portion still retains a substantially solid appearance to conceal the core. The method thus described may, of course, be varied and the equalization of the elasticity of the core and binding may be otherwise accomplished to attain the end in view, namely, that of producing a tie cord of this character in which both the core and binding have approximately the same breaking point.

In use, when a pull is exerted on the cord in tying, the binding grips about the core and its covering and due to the approximate equalization of the elasticity of the binding and core, a uniform resistance is offered to the pulling stresses and strains so that the maximum tensile strength is obtained. It, therefore, follows that the core and binding will break at approximately the same time when the breaking point of the cord is reached.

From the foregoing, it will thus be seen that a decorative tie cord has been devised which in addition to possessing the ornamental or decorative qualities set forth, possesses the necessary or requisite tensile strength while permitting of its production at a minimum cost.

What is claimed is:

1. A decorative tie cord including a core,

a covering therefor twisted with the core in the same direction and a binding spirally twisted about said core and covering whereby the covering is expanded or puffed away from the core and maintained by the binding.

2. A tie cord including a stranded core and a stranded covering therefor, said core and covering strands being twisted in the same direction and a binding of a different material from the core spirally twisted about said core and its covering in an opposite direction whereby the covering is expanded or puffed away from the core and maintained by the binding.

3. A tie cord including a stranded core and a stranded covering therefor, said core and covering strands being twisted in the same direction and a binding of a different material from the core spirally twisted about said core and its covering in an opposite direction whereby the covering is expanded or puffed away from the core and maintained by the binding, the said core and binding having substantially the same degree of elasticity.

4. A tie cord including a stranded core and a stranded covering therefor, said core and covering strands being twisted in the same direction and a binding extending helically about said core and its covering and pitched in an opposite direction with the covering strands puffed away from the core strands between the convolutions of the binding and thus maintained by the binding.

5. A decorative tie cord including a stranded core and a stranded covering therefor, said core and covering strands being twisted in the same direction and a binding having an inherently different degree of elasticity from the core treated to render the same of the same elasticity, said binding being spirally twisted about the core and its covering in an opposite direction whereby the covering strands are puffed away from the core strands and thus maintained by the binding.

6. A method of producing a tie cord of the character set forth including the steps of twisting together, in the same direction, the strands of a stranded core and the strands of a stranded covering and applying a binding helically around said covered core in an opposite direction to the direction of the twist of the core and binding strands whereby said covering strands are expanded or puffed away from the core between the convolutions of the binding.

7. A method of producing a tie cord of the character set forth including the steps of twisting together, in the same direction, the strands of a stranded core and the strands of a stranded covering and applying a binding helically around said covered core in an opposite direction to the direction of the twist of the core and binding strands and feeding the binding under a lesser tension than the

feeding tension of the core and covering strands and effecting an untwisting of the core and covering strands to a limited degree and causing the covering strands to expand or puff up about the core between the convolutions of the binding.

8. A method of producing a decorative tying cord of the character set forth including the steps of equalizing the elasticity of core and binding elements having inherently different degrees of elasticity, twisting together, in the same direction, the strands of the stranded core and the strands of a stranded covering and applying the binding helically around said covered core in an opposite direction to the direction of the twist of the core and binding strands.

9. A method of producing a decorative tying cord of the character set forth including the steps of equalizing the elasticity of core and binding elements having inherently different degrees of elasticity, twisting together, in the same direction, the strands of the stranded core and the strands of a stranded covering and applying the binding helically around said covered core in an opposite direction to the direction of the twist of the core and binding strands and feeding said binding under a lesser tension than the core and covering strands.

10. A method of producing a tie cord of the character set forth including the steps of twisting together the strands of the stranded core, applying a stranded covering helically around said core with the convolutions pitched in the direction of the twist of the core, and applying a binding helically around said covered core and pitched in the opposite direction to the direction of the twist of the core and binding strands, tensioning said core and binding to equalize the elasticity thereof and releasing said tension to permit the binding to backtwist a limited degree for causing the covering strands to expand or puff up about the core between the convolutions of the binding.
